FRANK B. EASTON, OF NEW YORK, N. Y.

GUARD AND INDICATOR FOR STORAGE VESSELS.

1,105,068.

Specification of Letters Patent. Patented July 28, 1914.

Application filed July 23, 1913. Serial No. 780,638.

To all whom it may concern:

Be it known that I, FRANK B. EASTON, a citizen of the United States, and a resident of New York, borough of Manhattan, in the county of New York and State of New York, have invented certain new and useful Improvements in Guards and Indicators for Storage Vessels, of which the following is a specification.

10 My invention relates to a guard and indicator designed to be attached to a storage vessel in position to shield the closure for the mouth of the same and capable of being moved to expose the closure when the contents of the vessel are needed for use. The presence of the guard and indicator and the necessity for moving it when the vessel is to be opened serve to remind one of the character of the vessel's contents; and the guard 15 and indicator is therefore especially adapted to be employed on bottles containing poison and other deleterious substances.

An important object of my invention is to incorporate with the guard and indicator 20 vice a signaling element of such a nature as to startle a careless, inexperienced, or ignorant person if the latter should handle or attempt to open the vessel to which my invention is applied. In this way a sufficient 25 warning is made certain of being given; and danger of the contents of the vessel being used by mistake practically eliminated.

The drawings illustrate one or more forms 30 of my invention and the manner of applying the same; and the reference numerals employed in connection with the various parts are the same throughout the several views.

On the drawings Figure 1 is a side elevation 35 of my guard and indicator with the parts in normal position on a storage vessel as a bottle, for example; Fig. 2 is a similar view of my invention with the parts moved to expose the closure of the storage vessel; Fig. 3 is a perspective view of a detail, showing the element which shields the closure of the storage vessel; Fig. 4 is a perspective view of a modified form of shielding element; and Fig. 5 is a side elevation showing another application of my invention.

40 These views illustrate a portion of a storage vessel, such as a bottle, having a body 1 with a neck 2 which receives a closure such as a cork 3. My guard and indicator is adapted to encircle the neck 2 and normally be in position to shield the closure 45 3 so that the latter cannot be withdrawn

till the guard and indicator is moved to expose the closure 3. When this is done the signaling element is actuated to give warning, this signaling element being indicated 60 by the numeral 4; and I preferably make this element in the shape of a device adapted to emit sparks, so that any one handling the vessel will at once be startled into taking notice of the nature of the vessel's contents, 65 as will be fully set forth hereinafter.

My guard and indicator comprises a shielding element 5, in the shape of a ring; and I employ a spiral spring 6 which engages the ring 5 and holds the ring in 70 shielding position. In the form shown in Figs. 1 and 2 the ring 5 is continuous and is provided with lugs 7 at one end, the lugs being bent inward to engage the flange 8 at the end of the neck 3. The body of the ring 75 with the lugs is made of some malleable metal, so that it can be slipped over the flange 8 and the lugs 7 afterward turned in with a convenient tool far enough to make them engage the flange 8 when the spring 6 80 forces the ring 5 into shielding position; but not too far to prevent the ring 5 from sliding freely on the neck 3. In the form shown on Fig. 4, the ring 5 is divided and consists of two halves 5^a and 5^b which are 85 held together with an encircling collar. This form of ring is provided with an in-turned flange 7' which serves the same purpose as the lugs 7 in the form shown in Figs. 1, 2 and 3. The spring 6 is preferably 90 secured to the ring 5 at one end, and at its other end it is secured to a clip 9 which encircles the neck and normally rests upon the shoulder of the vessel at the base of the neck 3. This clip is of flexible material, so that 95 it can be easily slipped into place; and its ends are fastened together by any suitable means such as a bolt or screw.

Referring now to the signal 4 I make the same comprise a leaf spring 10 fastened to 100 the clip 9 and extending toward the ring 5. The free end of the spring 10 carries a head 11 which has a pocket to receive a suitable sparking substance 12. The spring 10 is set so that it will hold the substance 12 against 105 the ring; and the ring will be provided with a collar 13 which extends outward from the face of the ring 5 and is roughened; so that when the substance 12 contacts with the collar it will scrape across the same and emit 110 sparks.

The substance 12 can be any suitable ma-

aterial that will emit sparks when struck or rubbed hard enough; such as for example a piece of flint or the metal cerium which sparks very easily when scratched, or any of the substances that are commonly used in 5 cigar lighters. It is forced tightly into the pocket in the head 11, and can be easily replaced when used up.

In the form shown on Figs. 1, 2 and 3 the 10 collar 13 is integral with the ring 5; while in the form shown on Fig. 4 the collar is made as a separate element and serves to bind the halves of the ring together. In this 15 form the collar should be made of some soft metal with its forward edge, referring to the direction of motion when the collar is forced upon the ring, of considerable thinness. This construction makes possible what is ordinarily known as a "press fit"; the collar 20 engaging the halves of the ring tightly as it is forced into place with the fingers and the thin edge adjusting itself to the outer surface of the ring. After the collar has been in place a few hours it will stick, owing 25 to the slight corrosion due to the action of the air; and the parts will be secured in operative position.

Fig. 5 shows my invention applied to a 30 bottle or vessel having the neck 2 in the bottom. This form of vessel is used for pills and other solid substances, and it rests upon a bottom flange 14 that conceals the cork 3. As the ring 5 is here held against the flange 8 by gravity when the bottle is lifted, I can 35 dispense with the spring 6. This vessel resting upon the flange 14 with the mouth downward, the ring 5 may be held up to a certain extent; but when the vessel is lifted the ring will drop till it is stopped by the flange 8. In the fall of the ring the collar 40 13 will strike sparks from the substance 12; and if they should escape notice, the repetition will not fail to be perceived when the ring 5 falls back upon the shoulder of the bottle when the mouth is turned up to remove the cork 3. The utility of my invention 45 will now be clear. The ring 5 shields the closure, and the closure cannot be taken out till the ring is moved to expose it, so that it can be seized with the fingers. The 50 presence of the ring and the need for moving it will serve to warn one that the bottle contains some substance such as poison; and in hospitals or sick rooms will ordinarily be 55 sufficient to cause an experienced nurse to take notice. Should the nurse be inexperienced or experienced but absent-minded, the action of the collar 13 striking sparks from the substance 12 will so startle her that 60 further carelessness will not be at all likely. In all the forms the ring 5 cannot be pushed far enough away from the closure to enable the substance 12 to pass the outer edge of the ring. Such a designing of the 65 parts is necessary to prevent the signal from

being used as a catch to hold the ring away from the cork; so that when the user is through with the bottle the ring will surely be moved back to shielding position with respect to the closure 3. I thus insure the 70 necessity of moving the ring and the operation of the signal before the contents of the vessel can be gotten at. I can also design the spring 6 to be too strong for children to compress. Furthermore the presence of the signal will ordinarily be sufficient to divert a child's attention from the contents of the bottle should it ever succeed in moving the ring 5 down far enough to produce 75 sparks with the collar 13.

Having described my invention, what I claim as new and desire to secure by Letters Patent of the United States is:—

1. A combined guard and indicator for the closure of a storage vessel comprising a 80 ring surrounding the closure and normally shielding the same, means for normally holding the ring in shielding position, said ring having a roughened collar thereon, and a sparking device adjacent to the ring and actuated by the collar to emit sparks when the ring is moved to expose the closure.

2. A combined guard and indicator for the closure of the neck of a storage vessel comprising a ring surrounding the closure and normally shielding the same, a spiral spring encircling said neck and acting to hold the ring in shielding position, a clip 95 encircling the neck, a leaf spring secured to the clip and extending therefrom and carrying a sparking substance at its free end in proximity to the ring, and a roughened collar on the ring to engage the substance and cause the same to emit sparks when the ring is moved to expose the closure.

3. A combined guard and indicator for the closure of a storage vessel comprising a ring surrounding the closure and having a roughened collar on its outer face, and a 100 sparking device adjacent to the ring and actuated by the collar to emit sparks when the ring is moved to expose the closure.

4. A combined guard and indicator for the closure of the neck of a storage vessel comprising a ring surrounding the closure, and carrying a roughened collar, a clip secured to the neck, a leaf spring secured to the clip and extending therefrom toward the collar, and carrying a sparking substance at its free end, whereby when the ring is moved the collar will cause the substance to emit sparks.

5. A combined guard and indicator for the closure of a storage vessel comprising means for guarding the closure and means for startling the vision when the guarding means and the vessel are moved relatively to each other to enable the vessel to be 125 opened.

6. A combined guard and indicator for the closure of a storage vessel comprising means for guarding the closure and means for emitting sparks when the guarding means and the vessel are moved relatively to each other to enable the vessel to be opened.
  7. A combined guard and indicator for the closure of a storage vessel comprising an element slidably mounted on said vessel and movable toward and from the body of said vessel to expose or shield the closure, said element having inward extending means to engage the vessel and prevent separation therefrom when moved away from the body of the vessel to shield the closure and having a roughened portion on its exterior surface to enable the element to be grasped by the hand to move the same toward the body of the vessel to expose the closure.
  8. A combined guard and indicator for the closure of a storage vessel comprising an element slidably mounted on said vessel and movable toward and from the body of the vessel to expose or shield the closure,

said element having inward extending means to engage the vessel and prevent separation therefrom when moved away from the body of the vessel to shield the closure and having a roughened portion on its exterior surface to enable the element to be grasped by the hand to move the same toward the body of the vessel to expose the closure, and a spring engaging the element and the vessel and acting to hold the element in shielding position. 30 35

9. A combined guard and indicator for the closure of a storage vessel comprising means for guarding the closure and means operated by the guarding means for startling the vision when the guarding means and the vessel are moved relatively to each other to enable the vessel to be opened. 40

Signed at New York in the county of
New York and State of New York this 11th 45
day of July A. D. 1913.
